UNITED STATES PATENT OFFICE.

HENRY TSCHERNING, OF FREEPORT, ILLINOIS, ASSIGNOR TO ARCADE MANUFACTURING COMPANY, OF FREEPORT, ILLINOIS, A CORPORATION OF ILLINOIS.

CORK-PULLER.

SPECIFICATION forming part of Letters Patent No. 728,520, dated May 19, 1903.

Application filed August 16, 1902. Serial No. 119,849. (No model.)

To all whom it may concern:

Be it known that I, HENRY TSCHERNING, a citizen of the United States of America, residing at Freeport, in the county of Stephenson 5 and State of Illinois, have invented certain new and useful Improvements in Cork-Fullers, of which the following is a specification.

My invention relates to certain new and useful improvements in cork-pullers; and its 10 object is to provide a device of this class which shall be simple, cheap, and effective.

To these and certain minor ends my invention consists in certain novel features of construction clearly shown in the drawings and 15 described in this specification.

In the aforesaid drawings, Figure 1 is a side elevation of my improved cork-puller, one of the side plates of the frame being removed. Fig. 2 is a similar view with the 20 parts in a different position, the nut and corkscrew-carrier, however, being shown in section. Fig. 3 is a section in the line 3 3 of Fig. 1. Fig. 4 is a section in the line 4 4 of Fig. 1, and Fig. 5 is a front view of the cork- 25 puller.

Referring to the drawings, A is the frame of my improved cork-puller, said frame being of the usual type, composed of two side plates A' A², secured together by suitable 30 bolts or screws. Certain portions of said plates form together a longitudinal guideway a, which opens through the front of the case in two openings a' and a², separated by a stop a³, formed by projecting portions upon 35 the side plates. In the guideway are the usual nut and corkscrew-carrier. The nut B is threaded to surround the corkscrew and is further provided with a projecting lug b, which extends into the opening a' and is 40 adapted by contact with the stop a³ to limit the upward movement of said nut B. The descending movement of said nut is limited by the bottom of the guideway a.

A corkscrew-carrier, represented by C, has 45 rotatably secured in it a corkscrew D provided with a cylindrical head d. The means by which the corkscrew is secured in the corkscrew-carrier is immaterial, any one of a number of common ways being possible. The 50 drawings clearly show the method used in

practice. A handle E, connected by a link e to the corkscrew-carrier, provides means for reciprocating the corkscrew-carrier throughout the entire length of the guideway a. A block F is pressed against the 55 head of the corkscrew D by a spring f, confined in a hole in the corkscrew-carrier C by a small screw f'. This acts as a frictional brake upon the corkscrew and retards its rotation in the corkscrew-carrier. This mechanism is more particularly described and claimed in my application on cork-pullers, filed on even date herewith and allotted Serial No. 119,848. A curved hook G is pivoted to the handle E at its junction with the link e, 60 and this hook is adapted during certain portions of the movement of the corkscrew-carrier to engage a notch b' in the nut B. A pin g extends laterally from the hook G and is adapted to be engaged by ribs a⁴, cast in 65 the side plates of the puller. The position of these ribs is such that during the upper half of the motion of the corkscrew-carrier the hook G is held away from and out of contact with the nut B, but during the lower 70 portion of the movement of the corkscrew-carrier it is permitted to fall by its own weight toward the nut B. Beveled surfaces a⁵ at the lower end of the ribs a⁴ provide for a gradual movement of the hook to and from 75 the nut.

The operation of the cork-puller will be apparent from the above to any one versed in the art. Starting with the parts in the position shown in Fig. 1, as the corkscrew-carrier goes downward the nut B also passes downward, remaining at the same distance from the corkscrew-carrier as that shown in Fig. 1. It is held at this distance because the frictional brake upon the corkscrew prevents the rotation of the corkscrew and consequent relative movement of the nut and corkscrew-carrier. When the nut B reaches the bottom of the guide-way, its motion is arrested, the force acting to rotate the corkscrew D becomes sufficient to overcome the force of the friction-brake, and the corkscrew-carrier comes up to the nut, the corkscrew passing through the nut and being screwed into the cork to be extracted. When 90

the parts reach the position shown in Fig. 2, the hook G, which has been permitted to swing toward the nut, engages the notch b' and connects the nut independently of the 5 corkscrew-carrier to the handle E. As the handle is lowered from the position shown in Fig. 2 it draws both the nut and carrier up at the same rate of speed, thereby extracting the cork. When the projection b upon 10 the nut B reaches the top of the slot a' and comes in contact with the stop a³, the progress of the nut is arrested. At the same moment the pin g meets the ribs a⁴, and the hook G is thrown out of engagement with the nut B, 15 thereby disconnecting the nut from the handle E. The corkscrew-carrier then rises alone, drawing the corkscrew through the nut and stripping the cork. This completes the cycle of operation.

20 The particular advantage of my construction lies in the fact that an independent pull is exerted upon the nut and carrier. Heretofore it has been customary to connect the nut to the carrier during certain portions of 25 the operation. I do not do this, but connect the nut independently of the carrier to the operating-handle, so that each of the two movable parts is independently and positively operated by the operating lever or handle.

30 I realize that considerable variations can be made in the details of this construction without materially departing from the spirit of the invention, and I do not limit myself to the specific form herein shown.

35 I claim as new and desire to secure by Letters Patent—

1. In a device of the class described, the combination with a frame, a corkscrew-carrier longitudinally reciprocable in said frame, a 40 handle and means of connection between said handle and said corkscrew-carrier whereby said handle can reciprocate said corkscrew-carrier, a nut also longitudinally reciprocable in said frame, and threaded to embrace said 45 corkscrew, and means for limiting the reciprocation of said nut, of means for connecting said handle to said nut to draw the same upward during the pulling motion of said corkscrew-carrier, and means for disconnecting 50 said nut from said handle at the termination of the pulling motion of said corkscrew-carrier, substantially as described.

2. In a device of the class described, the combination with a frame, a corkscrew-carrier 55 longitudinally reciprocable in said frame, a handle and means of connection between said handle and said corkscrew-carrier whereby said handle can reciprocate said corkscrew-carrier, a nut also longitudinally reciprocable 60 in said frame, and threaded to embrace said corkscrew, and means for limiting the reciprocation of said nut, of a hook pivotally connected to said handle, a notch in said nut and means for bringing said hook into engagement with said nut to connect it to said 65 handle, substantially as described.

3. In a device of the class described, the

combination with a frame, a corkscrew-carrier longitudinally reciprocable in said frame, a handle and means of connection between said handle and said corkscrew-carrier whereby said handle can reciprocate said corkscrew-carrier, a nut also longitudinally reciprocable in said frame, and threaded to embrace said corkscrew, and means for limiting the reciprocation of said nut, of a gravity-hook pivoted to said handle, a notch in said nut, said gravity-hook being adapted to fall into engagement with said nut of its own weight 75 to connect said nut to said handle, substantially as described.

4. In a device of the class described, the combination with a frame, a corkscrew-carrier longitudinally reciprocable in said frame, a handle and means of connection between said 80 handle and said corkscrew-carrier whereby said handle can reciprocate said corkscrew-carrier, a nut also longitudinally reciprocable in said frame, and threaded to embrace said corkscrew, and means for limiting the reciprocation of said nut, of a hook pivoted to said handle and adapted to engage said nut, and means for disengaging said hook from said nut, substantially as described.

5. In a device of the class described, the combination with a frame, a corkscrew-carrier longitudinally reciprocable in said frame, a handle and means of connection between said handle and said corkscrew-carrier whereby said handle can reciprocate said corkscrew-carrier, a nut also longitudinally reciprocable in said frame, and threaded to embrace said corkscrew, and means for limiting the reciprocation of said nut, of a hook pivoted to said handle and adapted to engage said 90 nut, and means for disengaging said hook from said nut, substantially as described.

6. In a device of the class described, the combination with a frame, a corkscrew-carrier 100 longitudinally reciprocable in said frame, a handle and means of connection between said handle and said corkscrew-carrier whereby said handle can reciprocate said corkscrew-carrier, a nut also longitudinally reciprocable in said frame, and threaded to embrace said corkscrew, and means for limiting the reciprocation of said nut, of a hook pivoted to said handle and adapted to engage said 105 nut, and a cam in said case adapted to engage said hook and throw the same out of engagement with said nut, substantially as described.

7. In a device of the class described, the combination with a frame, a corkscrew-carrier 110 longitudinally reciprocable in said frame, a handle and means of connection between said handle and said corkscrew-carrier whereby said handle can reciprocate said corkscrew-carrier, a nut also longitudinally reciprocable 115 in said frame, and threaded to embrace said corkscrew, and means for limiting the reciprocation of said nut, of a hook pivoted to said handle and adapted to engage said nut, pro-

- jecting pins on said hook and a cam on said case, adapted to engage said projecting pins to disengage said hook from said nut, substantially as described.
- 5 8. In a device of the class described, the combination with a frame, a corkscrew-carrier longitudinally reciproable in said frame, a handle and means of connection between said handle and said corkscrew-carrier whereby
- 10 said handle can reciprocate said corkscrew-carrier, a nut also longitudinally reciproable in said frame, and threaded to embrace said corkscrew, and means for limiting the reciprocation of said nut, of a hook pivoted to said handle, and adapted to engage said nut and a pair of ribs forming cams cast integrally with said case and adapted to engage said hook to disengage it from said nut, substantially as described.
- 15 9. In a device of the class described, the combination with a frame, a corkscrew-carrier longitudinally reciproable in said frame, a
- 20 handle and means of connection between said handle and said corkscrew-carrier whereby said handle can reciprocate said corkscrew-carrier, a nut also longitudinally reciproable in said frame, and threaded to embrace said corkscrew, and means for limiting the reciprocation of said nut, of a gravity-hook pivoted to said handle and adapted to engage said nut, projecting pins on said hook, a pair of ribs forming cams cast integrally with said case and adapted to throw said hook away from said nut and disengage it therefrom, substantially as described. 35

In witness whereof I have hereunto set my hand, at Freeport, in the county of Stephenson and State of Illinois, this 29th day of July, A. D. 1902.

HENRY TSCHERNING.
